UNITED STATES PATENT OFFICE.

EDWIN E. SLICK, OF PITTSBURGH, PENNSYLVANIA, ASSIGNOR TO UNITED STATES
GLASS COMPANY, OF PITTSBURGH, PENNSYLVANIA.

DESIGN FOR A CONDIMENTS HOLDER.

Application filed October 10, 1927. Serial No. 23,710. Term of patent 14 years.

To all whom it may concern:

Be it known that I, EDWIN E. SLICK, a citizen of the United States, residing at Pittsburgh, in the county of Allegheny and State of Pennsylvania, have invented a new, original, and ornamental Design for a Condiment Holder, of which the following is a specification, reference being had to the accompanying drawing, forming part thereof.

The figure is an elevational view slightly in perspective of a condiment holder showing my new design.

I claim:

The ornamental design for a condiment holder, as shown.

EDWIN E. SLICK.
